UNITED STATES PATENT OFFICE

JOHANNES NEFF, OF DRESDEN, GERMANY, ASSIGNOR TO THE FIRM UNIVERSELLE CIGARETTEN-MASCHINEN-FABRIK J. C. MULLER & CO., OF DRESDEN, GERMANY

APPARATUS FOR PACKETING GOODS

Application filed November 29, 1930, Serial No. 499,014, and in Germany April 8, 1930.

The present invention is a continuation in part of my copending application Ser. No. 409,292, filed Nov. 23, 1929.

Apparatus for packeting cigarettes or other goods are well known in many forms. In such apparatus it has been proposed to provide means, which on the insertion of the goods in the packet or box permit of enclosing them in one or more wrappings for example of parchment paper, tin foil or the like.

In the apparatus of the present invention the goods, for example cigarettes, are inserted in an open packet, the goods being wrapped at the same time in two different wrappers.

In accordance with the invention there is provided a turntable rotated intermittently between a fixed cover plate and a bottom plate and provided on its periphery with pockets to receive the goods. In addition there is provided a feeding device for a wrapper strip (for example of parchment paper) so arranged that the strip is placed in front of a pocket into which the goods are pushed taking the strip with them. Then on further movement of the turntable and on folding inwards the projecting ends of the strip, if any, at another position of the pocket of the turntable containing the goods a second wrapper strip is positioned transversely of the first strip, the goods wrapped in the first strip being pushed by a plunger entraining the second transverse strip into the packet or box placed in front of it.

The goods wrapped only in one strip are ejected from the pocket containing them by an entraining member movable radially in an opening in the stationary cover plate and deposited on the second wrapper strip which is positioned in front of a shaping channel located externally of the turntable. The shaping channel is arranged thus externally of the turntable and the goods are fed by means of an entraining member from the pocket on the turntable in front of the shaping channel.

It is thus possible by simple means to wrap the goods as it were crosswise in the two strips. The means for folding the projecting strip ends may be directly connected with the

turntable and operated by means which effect intermittent rotation of the turntable.

The invention is illustrated in the accompanying drawings which show by way of example one embodiment of the improved apparatus.

Fig. 1 is a plan view of my apparatus;

Fig. 2 is a full sectional view along line 2—2 of Fig. 1 seen in the direction of the arrows;

Fig. 3 is a sectional detail of a portion of Fig. 1 seen in the direction of the arrow y' thereof;

Figs. 4 and 5 respectively show the same detail of Fig. 3 in two different operating positions;

Fig. 6 is a partial sectional detail along line 2—2 of Fig. 1;

Fig. 7 is a side view of Fig. 6 seen in the direction of the arrow W;

Fig. 8 is a section viewed in the direction of the arrows along line 8—8 of Fig. 1; and

Fig. 9 is a section viewed in the direction of the arrows along line 9—9 of Fig. 1.

Referring to the drawings, the machine is mounted in the frame A. B is a belt pulley for the main drive, C the driving shaft on which the pinion D and the worm wheel F are mounted. The latter moves the plunger 2 backwards and forwards through the medium of the crank H and double-armed lever I.

The group of cigarettes G arranged in two superposed layers is fed between guide bars 1 and 1' by the plunger 2 into the pocket 3 on the turntable 4, which is provided with six such pockets, taking with it the wrapper strip E (for example of parchment paper) placed in front of it. The wrapper strip E is drawn from a spool 5 in known manner between the pair of knives 6 and a pair of gripping jaws 7 and led in front of the opening in the pocket 3, the gripping jaws 7 serving to hold the wrapper strip after it has been severed by the pair of knives 6 until it is engaged by the group of cigarettes entering the pocket.

The turntable 4 is rigidly connected to an intermediate member 4' rotatably mounted on the vertical spindle 8, the lower part of

which member 4' is formed with ratchet teeth 9. In the ratchet teeth 9 engages a resilient pawl 10 arranged on the carrier 11. The carrier 11 has a lug 11' embracing the upright spindle 8 and is swung to and fro by means of a connecting rod 12 pivoted thereto through the medium of a crank 13, as a result of which the intermediate member 4' and the turntable connected therewith is turned each time through 60°, i. e. an amount corresponding to the distance apart of the pockets.

On inserting a group of cigarettes in the pocket 3 the downwardly projecting end of the wrapper strip E remains for the moment in the vertical position. On rotation of the turntable 4 this strip end is pushed by the cam 14 into the horizontal position.

At an angle of 60° to the direction of the guide track 1 and 1' is arranged a flap folder which in its initial position is in the position shown in Fig. 4, i. e. is horizontal. This flap folder is secured to a pinion 16 mounted on the pivot 17' of the slide 17. On a lateral projection 18 on the slide 17 is mounted a pinion 19 which meshes with the pinion 16 and also with a stationary rack bar 20. A spring 21 connected to the lower end of the slide tends to draw the slide downwards. On the slide is also mounted a guide roller 22 which co-operates with a cam 23 provided on the pawl carrier 11. The cam 23 inclines in the direction of the arrow α shown in Fig. 1, so that on rotation of the turntable 4 in the direction of the arrow y indicated in Fig. 1 the roller 22 and therewith the slide 17 are moved downwards, while on the return movement of the pawl carrier the roller 22 and therewith the slide 17 are moved upwards by the cam 23, the flap folder 15 and the end of the wrapper strip E resting thereon being moved into the vertical position shown in Fig. 3. On the pawl carrier reaching the initial position shown in Fig. 1 the roller 22 and the slide 17 connected therewith have been pushed upwards to the extent shown in Fig. 5. The flap folder is thus moved further into the horizontal position through the recess 24' in the stationary cover plate 24 and places the end of the wrapper strip on the group of cigarettes.

On the further rotation of the turntable through 60° the group of cigarettes embraced by the wrapper strip is turned into the position indicated at Z in Fig. 1, the corresponding lower edge on the recess 24' being so shaped as to prevent the end of the wrapper strip striking against it. During the swinging movement of the pawl carrier in the direction of the arrow y' indicated in Fig. 1 the slide 17 has been moved downwards so that the flap folder 15 has moved into the position shown in Fig. 4 and the projecting end of the wrapper strip of the next group of cigarettes rests thereon.

The group of cigarettes provided with the wrapper strip now passes into the position shown at X in Fig. 1. At this point, as shown in detail in Figs. 6 and 7, there is arranged a slide 25 movable radially of the turntable. On the slide 25 is provided a pin 26 which is engaged by the forked end 27' of the lever 27. The lever 27 is mounted at 28 on a bracket arm 29 and is operated by the link 30 connected thereto at 31. The other end of the link 30 is mounted on the crank pin 32 on the disc 33. On the slide 25 is also mounted a pusher member 34 which turns about the pivot 34' which is held by a spring 35 in the full line position shown in Figs. 6 and 7. If now the lever 27 is moved by the crank mechanism 32 into the position shown in dotted lines in Fig. 6 the slide is pushed in the direction of the arrow shown in Fig. 6. The group of cigarettes C' is thus engaged by the lower end of the pusher member 34 projecting into the pocket 3 on the turntable and is pushed from the pocket 3. The wrapper strip E' lying in front of the rear ends of the cigarettes will ensure that the complete group is pushed as a whole to the stop 36 even although the pushed member is cut away as shown in Fig. 7. The upper guide bar 37 is so formed that on ejection of the group of cigarettes the ends of the wrapper strip do not fall. For this purpose the forward edge 37' of the guide bar is extended close to the die 38.

Before the group of cigarettes is pushed in the manner above described over the shaping channel 39 a second wrapper strip E² is placed by known means on the hinged flaps 40 which facilitate the introduction of the group of cigarettes into the packets S. The open boxes are fed on the guide track 41 in the direction of the arrow U shown in Fig. 1 to the shaping channel 39. The die 38 is mounted with its spindle 38' in a lug 29' in the bracket arm 29 and is vertically movable. On a pin 42 provided on the spindle 38' engages the forked end 43' of the bell-crank lever 43 movable about the pivot 44. By means of a spring 45 connected to the rear end of the bell-crank lever 43, the bell-crank lever 43 with its guide roller 46 is drawn against the cam disc 33.

As soon as the group of cigarettes passes between the wrapper strip E² and the die 38, the die 38 is moved downwards, the introduction of the cigarettes into the boxes being ensured by the flaps 40. On further downward movement of the die 38, the die 47 acting as an abutment recedes correspondingly so that the flaps 40 are withdrawn from the box. When the die 47 reaches the position shown in Fig. 2 and after the die 38 has again been raised, the work is taken away by known means in the direction of the arrow V indicated in Fig. 1 into a channel. On its way to the channel the still projecting ends of the

wrapper strip is folded over in known manner.

After the group of cigarettes is inserted in the manner described by means of the die 38, the pusher member 34 is moved by means of the lever 48 into the position shown in dash and dot lines in Fig. 6. On retraction of the slide 25 the edges 49 of the cut away portion in the pusher plate 34 come in contact with the guide bars 37 so that on further retraction of the slide into initial position the pusher plate 34 is moved out of the path of the turntable 4. The turntable 4 can be further rotated after the pusher member is moved out of its path. When the slide is returned to its initial position the pusher plate under the action of the spring is again moved into the position shown in Fig. 6. For this purpose corresponding cut away portions 37² will be provided on the guide bar 37.

The lever 48 which ensures operation of the plate 34 in the forward position is rotatable about the pivot 50 and bears with its rear end 48' which is provided with a roller on the cam disc 33. A spring 51 secured to the frame at 52 presses the lever against the cam track.

The die 47 with its spindle 47' is mounted in a lug 53 and is moved up and down from the shaft K by means of a crank disc 58, a connecting rod 54 and a lever 57 pivoted at 55 in a bearing bracket 56.

The shaft K is driven by the pinions D, D' from the driving shaft C and itself drives the shaft 60 and the disc 33 mounted thereon through the worm wheel 59.

What I claim is:

1. Apparatus for packeting goods and at the same time enwrapping the goods, comprising in combination with a turntable formed with pockets to receive the goods and a stationary cover plate and a bottom plate for such turntable, means for positioning a wrapper strip in front of a pocket, a plunger for pushing the goods into the pocket entraining the wrapper strip, means for intermittently rotating the turntable and for folding the ends of the wrapper strip, means for moving said goods radially out of said pocket and over a second wrapper strip lying transversely of the first mentioned wrapper strip and a second plunger for pushing the partially enwrapped goods into a packet and entraining the second wrapper strip.

2. Apparatus for packeting goods and at the same time enwrapping the goods, comprising in combination with a turntable formed with pockets to receive the goods and a stationary cover plate formed with openings and a bottom plate for such turntable, means for positioning a wrapper strip in front of a pocket, a plunger for pushing the goods into the pocket entraining the wrapper strip, means for intermittently rotating the turntable including pawl and ratchet mechanism and a carrier for said pawl, means for folding the ends of the wrapper strip, said means including a cam on the bottom plate for raising the projecting end of the wrapper strip on rotation of the turntable, a cam carried by said pawl carrier and a flap folder operable by said last mentioned cam to insert the end of said wrapper strip through an opening in the cover plate and place it on the goods in the pocket, means for moving said goods radially out of said pocket and over a second wrapper strip lying transversely of the first mentioned wrapper strip and a second plunger for pushing the partially enwrapped goods into a packet and entraining the second wrapper strip.

nism and a carrier for said pawl, means for folding the ends of the wrapper strip, said means including a cam carried by said pawl carrier and a flap folder operable by said cam to insert the end of said wrapper strip through an opening in the cover plate and place it on the goods in the pocket, means for moving said goods radially out of said pocket and over a second wrapper strip lying transversely of the first mentioned wrapper strip and a second plunger for pushing the partially enwrapped goods into a packet and entraining the second wrapper strip.

3. Apparatus for packeting goods and at the same time enwrapping the goods, comprising in combination with a turntable formed with pockets to receive the goods and a stationary cover plate and a bottom plate for such turntable means for positioning a wrapper strip in front of a pocket, a plunger for pushing the goods into the pocket entraining the wrapper strip leaving a projecting end, means for intermittently rotating the turntable and for folding the ends of the wrapper strip, including a cam on the bottom plate for raising the projecting end of the wrapper strip on rotation of the turntable, means for moving said goods radially out of said pocket and over a second wrapper strip lying transversely of the first mentioned wrapper strip and a second plunger for pushing the partially enwrapped goods into a packet and entraining the second wrapper strip.

4. Apparatus for packeting goods and at the same time enwrapping the goods comprising in combination with a turntable formed with pockets to receive the goods, a stationary cover plate formed with openings and a bottom plate for such turntable, means for positioning a wrapper strip in front of a pocket, a plunger for pushing the goods into the pocket entraining the wrapper strip leaving a projecting end, means for intermittently rotating the turntable including pawl and ratchet mechanism and a carrier for said pawl, means for folding the ends of the wrapper strip, said means including a cam on the bottom plate for raising the projecting end of the wrapper strip on rotation of the turntable, a cam carried by said pawl carrier and a flap folder operable by said last mentioned cam to insert the end of said wrapper strip through an opening in the cover plate and place it on the goods in the pocket, means for moving said goods radially out of said pocket and over a second wrapper strip lying transversely of the first mentioned wrapper strip and a second plunger for pushing the partially enwrapped goods into a packet and entraining the second wrapper strip.

5. Apparatus for packeting goods and at the same time enwrapping the goods, comprising in combination with a turntable formed with pockets to receive the goods

and a stationary cover plate formed with openings and a bottom plate for such turn-table, means for positioning a wrapper strip in front of a pocket, a plunger for pushing the goods into the pocket entraining the wrapper strip leaving a projecting end, means for intermittently rotating the turn-table including pawl and ratchet mechanism and a carrier for said pawl, means for folding the ends of the wrapper strip, said means including a cam carried by said pawl carrier, a slide operable by said cam, a rack and pinions operable by said slide and a flap folder operable by said rack and pinions to insert the end of said wrapper strip through an opening in the cover plate and place it on the goods in the pocket, means for moving said goods radially out of said pocket and over a second wrapper strip lying transversely of the first mentioned wrapper strip and a second plunger for pushing the partially enwrapped goods into a packet and entraining the second wrapper strip.

6. Apparatus for packeting goods and at the same time enwrapping the goods comprising in combination with a turntable formed with pockets to receive the goods and a stationary cover plate formed with a recess and a bottom plate for such turntable, means for positioning a wrapper strip in front of a pocket, a plunger for pushing the goods into the pocket entraining the wrapper strip, means for intermittently rotating the turntable including pawl and ratchet mechanism and a carrier for said pawl, means for folding the ends of the wrapper strip, said means including a cam carried by said pawl carrier and a flap folder operable by said cam to insert the end of said wrapper strip through an opening in the cover plate and place it on the goods in the pocket, pusher means movable radially in the recess in the stationary cover plate for the turntable for depositing the goods about which said first wrapper strip has been folded over a second wrapper strip lying transversely of the first mentioned wrapper strip in front of a shaping channel externally of the turntable and means for pushing the partially enwrapped goods into a packet and entraining said second wrapper strip.

7. Apparatus for packetting goods and at the same time enwrapping the goods comprising in combination with a turntable formed with pockets to receive the goods and a stationary cover plate formed with a recess and a bottom plate for such turntable, means for positioning a wrapper strip in front of a pocket, a plunger for pushing the goods into the pocket entraining the wrapper strip, means for intermittently rotating the turntable including pawl and ratchet mechanism and a carrier for said pawl, means for folding the ends of the wrapper strip, said means including a cam carried by said pawl.

carrier and a flap folder operable by said cam to insert the end of said wrapper strip through an opening in the cover plate and place it on the goods in the pocket, pusher means movable radially in the recess in the stationary cover plate for the turntable for depositing the goods about which said first wrapper strip has been folded over a second wrapper strip lying transversely of the first mentioned wrapper strip in front of a shaping channel externally of the turntable, said pusher means including a resilient flap, said flap formed with recesses and a guide bar cooperating with said flap, and means for pushing the partially enwrapped goods into a packet and entraining said second wrapper strip.

8. Apparatus for packeting goods and at the same time enwrapping the goods, comprising in combination with a turntable formed with pockets to receive the goods and a stationary cover plate formed with a recess and a bottom plate for such turntable, means for positioning a wrapper strip in front of a pocket, a plunger for pushing the goods into the pocket entraining the wrapper strips, means for intermittently rotating the turntable including pawl and ratchet mechanism and a carrier for said pawl, means for folding the ends of the wrapper strip, said means including a cam carried by said pawl carrier and a flap folder operable by said cam to insert the end of said wrapper strip through an opening in the cover plate and place it on the goods in the pocket, pusher means movable radially in the recess in the stationary cover plate for the turntable for depositing the goods about which said first wrapper strip has been folded over a second wrapper strip lying transversely of the first mentioned wrapper strip in front of a shaping channel externally of the turntable, said pusher means including a resilient flap, said flap formed with recesses and a guide bar co-operating with said flap and means for pushing the wrapped goods into a packet and thereby entraining said second wrapper. 110

1 9. Apparatus for packing goods and at
1 the same time enwrapping the goods, comprising in combination with a turntable
1 formed with pockets to receive the goods and
1 a stationary cover plate formed with a recess
1 and a bottom plate for such turntable, means
1 for positioning a wrapper strip in front of
1 a pocket, a plunger for pushing the goods into
1 the pocket entraining the wrapper strip, means for intermittently rotating the turntable including pawl and ratchet mechanism and a carrier for said pawl, means for folding the ends of the wrapper strip, said means including a cam carried by said pawl carrier and a flap folder operable by said cam to insert the end of said wrapper strip through an opening in the cover plate and place it on the goods in the pocket, pusher means movable
115
